UNITED STATES PATENT OFFICE.

WILLIAM R. FORSYTH, OF SWAMPSCOTT, MASSACHUSETTS, ASSIGNOR TO WILLIAM FORSYTH & SONS COMPANY, OF WEST LYNN, MASSACHUSETTS, A CORPORATION OF MASSACHUSETTS.

DIE-BLOCK.

1,158,670.

Specification of Letters Patent.

Patented Nov. 2, 1915.

Application filed February 21, 1912. Serial No. 679,202.

To all whom it may concern:

Be it known that I, WILLIAM R. FORSYTH, a citizen of the United States, and resident of Swampscott, in the county of Essex and 5 State of Massachusetts, have invented certain new and useful Improvements in Die-Blocks, of which the following is a specification.

This invention relates to die blocks which 10 are used in die presses for dieing out leather or other sheet material, and especially to that class of die blocks which comprise a plurality of wood sections and wood dowels.

The invention consists in the combination 15 of arrangements of the dowels, on the one hand, and of the grain of the dowels and sections, on the other hand, whereby the dowels may sustain the working stresses as between the sections to keep the working 20 surfaces of the several sections flush with each other, and whereby the grain of the dowels, as well as that of the sections, shall extend from top to bottom of the block.

Of the accompanying drawings, which 25 illustrate the invention: Figure 1 represents an elevation of a plurality of wood sections of a die block having wood dowels arranged to sustain the working stresses as between the sections. Fig. 2 represents a perspective 30 view of a wood dowel shaped to conform to the grooves formed in the wood sections as shown by Fig. 1. Fig. 3 represents an elevation of a plurality of wood sections which differ from those shown in Fig. 1 in 35 that the grooves therein are undercut to hold the sections against lateral separation. Fig. 4 represents a perspective view of a wood dowel shaped to conform to the undercut grooves shown in Fig. 3.

40 The same reference characters indicate the same parts wherever they occur.

Referring first to Fig. 1,—a plurality of wood sections 10 are arranged side by side in contiguous relation to form a die block. 45 There may be as many sections as may be necessary to provide a block of the required size. The sections are arranged in such manner that the grain of the wood extends from the top surface 11 to the bottom surface 50 face 12. The confronting portions of the

several sections are formed with registering grooves which extend transversely of the grain to provide stress-sustaining shoulders 15 and 16. The said shoulders and the surfaces 14 of each pair of registering grooves 55 form a chamber for a stress-sustaining dowel 13. The shoulders 15 and 16 intersect the grain of the sections, and in this form they are rectangular.

Wood dowels such as that shown by Fig. 2 are used with sections grooved as shown by Fig. 1. Each dowel is shaped to conform to the chamber formed by a pair of registering grooves in two contiguous sections 10. The peculiar thing about the 60 dowels is that their grain ends are exposed at the surfaces 18 and 19 which engage the shoulders 15 and 16 of the sections. The surfaces 17, 17 of the dowels engage the surfaces 14, 14 of the sections. The grain 65 ends of the dowels are thus caused to occupy abutting end-to-end relation with the grain ends which are exposed at the shoulders 15 and 16. The significance of this arrangement is that the die block is characterized 70 by a uniform arrangement of grain in both sections and dowels, in consequence of which any swelling or shrinking action of the wood will be uniform in the sections and dowels 75 and will avoid separation of the sections 80 from this cause. In all die blocks having stress-sustaining dowels as hitherto made, the direction of the grain of the dowels has, so far as I am aware, been transverse to the direction of the grain of the sections, and 85 has caused separation of the sections in consequence of swelling and shrinking. Such separation is accounted for as follows. Referring first to the sections 10, 10, a swelling action of the wood causes the surfaces 14, 14 90 to move away from each other, and a shrinking action causes them to approach each other. The distance between the shoulders 15 and 16, however, does not vary, because swelling and shrinking does not operate in 95 the direction of the grain of the wood. Now, if the registering grooves are occupied by a dowel whose grain extends horizontal and parallel to the planes of division of the sections, a swelling action will cause a nor- 100

mal horizontal swelling which will be commensurate with the separating movement of the surfaces 14. At the same time there will be a tendency for the dowels to swell vertically against the shoulders 15 and 16; but since the latter do not move apart under any swelling action, the vertical swelling tendency of the dowels must find relief in some other direction. Hence the normal horizontal swelling of the dowels is augmented by the tendency to swell vertically, and the aggregate horizontal swelling of the dowels is therefore substantially greater than the horizontal swelling of the sections between the planes of the surfaces 14. The contiguous faces of the sections would thus be forced apart by the swelling of a dowel formed and arranged as the practice hitherto has dictated.

Some manufacturers have defeated the splitting or spreading action above explained by making the dowels considerably smaller than the grooves in which they are arranged, thus allowing clearance for vertical swelling of the dowels. The objection to such practice is that it also defeats the primary purpose of the dowels, which is to sustain the working stresses as between the sections and maintain the sections in flush relation at the working surface. Another undesirable result would follow if the sections and dowels as hitherto assembled contained the maximum degree of moisture when assembled and should undergo a shrinking action. In that case there would be a horizontal shrinking of the sections between the planes of the surfaces 14, which would cause said surfaces to approach each other. The shoulders 15 and 16, however, would not approach each other, and the dowel receiving chamber would contract horizontally but not vertically. The dowel, with its grain extending horizontally, would not only shrink in accordance with the movement of the surfaces 14, but it would shrink vertically, and even though the dowel be fitted tightly in the beginning, it would recede from the shoulders 15 and 16 and permit relative vertical movement of the sections. Such movement would be caused by the working stresses and would destroy the working surface of the block. These difficulties are both overcome by cutting the dowels, according to my invention, so that their grain will be parallel to the grain of the sections.

The modification shown by Figs. 3 and 4 embodies the desirable features hereinbefore described and explained, and embodies an additional feature, namely, that the registering grooves of the sections 10^x are of dovetail formation, having undercut shoulders 15^x, 16^x, and vertical surfaces 14^x,

while the dowels 13^x are shaped to conform to said registering grooves. The grain of the dowels 13^x extends vertically as does that of the sections 10^x. The dowels thus serve to hold the sections positively against lateral separation.

In the form shown by Fig. 1 it would be desirable to use glue upon the contiguous faces of the sections 10 and also upon the dowels. It would be desirable also to use glue in the same manner with the form shown by Fig. 3; but since the sections 10^x in Fig. 3 are held positively against lateral separation, by the dowels, glue might be omitted without depriving the block wholly of means for holding the sections against each other.

The described arrangement of the grain, according to my present invention, gives the dowels a greater stress-sustaining power than the dowels would have if their grain extended horizontally according to former practice. This is because there is a shearing tendency as between the diagonal stress-sustaining shoulders of contiguous sections of the block. This shearing strain is sustained by the grain ends of my dowels, whereas if the grain extended horizontally the shearing strain would be upon the sides of the grain and there would not be so many grains available to sustain it.

Having thus explained the nature of my said invention and described a way of constructing and using the same, although without attempting to set forth all the forms in which it may be made or all the modes of its use, what I claim is:

1. A die block comprising wood sections arranged side by side in contiguous relation, the grain of said sections extending from top to bottom, the confronting faces of said sections having co-operative registering grooves extending transversely of said grain and providing stress-sustaining shoulders intersecting said grain, and wood dowels each occupying a pair of said registering grooves and conforming thereto, the grain of said dowels extending transversely of said grooves and substantially parallel to the grain of said sections, whereby the grain ends of said dowels are in abutting end to end relation with the grain ends of said shoulders.

2. A die block comprising wood sections arranged side by side in contiguous relation, the grain of said sections extending from top to bottom, the confronting faces of said sections having co-operative registering undercut grooves extending transversely of said grain and providing undercut stress-sustaining shoulders intersecting said grain, and wood dowels each occupying a pair of said registering grooves and conforming to

the undercut formation of the latter, the grain of said dowels extending transversely of said grooves and substantially parallel to the grain of said sections, whereby the 5 grain ends of said dowels are in abutting end to end relation with the grain ends of said shoulders.

In testimony whereof I have affixed my signature, in presence of two witnesses.

WILLIAM R. FORSYTH.
